UNITED STATES PATENT OFFICE.

FRANK CONRAD, OF SWISSVALE, PENNSYLVANIA, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

ELECTRICAL APPARATUS.

1,106,368.

Specification of Letters Patent. Patented Aug. 11, 1914.

Application filed April 10, 1908. Serial No. 426,310.

To all whom it may concern:

Be it known that I, FRANK CONRAD, a citizen of the United States, and a resident of Swissvale, in the county of Allegheny and State of Pennsylvania, have invented a new and useful Improvement in Electrical Apparatus, of which the following is a specification.

My invention relates to electrical apparatus and it has special reference to devices for converting alternating currents into direct currents and for automatically regulating uni-directional currents so produced.

One object of my invention is to provide an improved structure in which a current-rectifying device and a regulator may be associated with a view to obtaining simplicity of construction and efficiency in operation.

A further object of my invention is to so construct a current-rectifying device that it may be readily removed from a casing containing both the rectifier and the regulator in order that it may be conveniently replaced or repaired without delay and without tending to injure the electric circuit connections with the regulator.

It is frequently desirable to supply a substantially constant uni-directional current to a circuit from which translating devices are supplied such, for example, as a series arc light circuit and it has been proposed to utilize a current-rectifying device, which may be a well known form of mercury vapor converter, in conjunction with a constant current regulator, in order that single-phase alternating current energy may be adapted for the aforesaid purposes.

According to my present invention, I provide a relatively simple and compact structure which is well adapted to fulfil the demands of commercial service and to effect the aforesaid objective results, and it embodies a number of improvements which are more fully brought out in the following specification and in the appended claims.

Figures 1 and 2 of the accompanying drawings are elevations at right angles to each other of a device constructed in accordance with my invention. Fig. 3 is a partially sectional elevation of the current-rectifying device and its supports, the details of which are shown in Figs. 4, 5, and 6. Figs. 7 and 8 are views, in elevation and in plan, respectively, of the starting trans-

former which also forms a part of the device shown in Figs. 1 and 2. Fig. 9 is a diagrammatic view showing the electric circuit arrangement and connections of a system embodying the various instrumentalities which are associated in the assembled device. 55

Referring to the drawings, the device here illustrated comprises a substantially rectangular core member 1 with which stationary coils 2 and 3 and movable coils 4 and 5 are associated, a rectifying device 6, a starting 65 transformer 7 therefor and an inclosing casing 8 having a cover member 9 to which all of the other parts are secured.

The magnetizable core member is preferably composed of iron or steel laminæ 70 which are clamped between side frames 10 by means of bolts 11, the said frames being also clamped to the cover member 9 by means of bolts 11a. Since the side frames 10 extend from the bottom to the top of the 75 tank 8, the side walls of the tank are largely relieved from the weight of the structure. The said frames 10 are provided with a plurality of projections on which the current-rectifying device 6 and the starting trans- 80 former 7 are supported.

The cover 9 is provided with standards 12 and 13 and sheaves or pulleys 14 and 15 are mounted upon a shaft 16 which is supported in bearings in the said standards. 85

The core member 1 is provided with an intermediate leg 17 which is surrounded by the movable coils 4 and 5 and the stationary coils 2 and 3, in a well known manner, the movable coils being supported from the 90 sheaves or pulleys 14 and 15. Each of the movable coils 4 and 5 is provided with coil supports or clamping frames 18 located on the respective sides of the coils in order to guide their movement and to provide suitable means whereby connection may be made between suitable supporting cords 19, which pass over the pulleys 14 and 15, and the coils 4 and 5. According to the usual practice for regulators, one end of one coil 100 and the opposite end of the other are connected to the same cord, so that, when the coils recede from or approach each other, the two pulleys are turned in opposite directions. 95

The current-rectifying device 6 comprises a vacuum bulb 20 which may be of any suitable structure that is adapted to convert

single-phase alternating current energy into uni-directional energy, the bulb illustrated being provided with positive terminals 21 and 22 and negative terminals 23 and 24, as shown in Fig. 3. The bulb is provided with a suitable amount of mercury which vaporizes, in a well-known manner, during the operation of the converter. The bulb is mounted on a rocking frame 25 and is partially surrounded by a box 26, the rocking frame being pivotally secured to ear projections 27 on the sides of the box.

The base of the box 26 comprises an insulating plate 28 having a plurality of contact members 29, 30, 31, and 32 resiliently secured to it. The contact members are in the form of bolts which extend through holes 33 in the plate 28 and are provided with set nuts 34, by means of which electric circuit connections may be established between the rectifier terminals and the contact members, and with enlarged lower ends to serve as contact terminals. The lower ends of the holes 33 are enlarged to form recesses 36 for the enlarged lower ends of the bolts, and springs 35 are interposed between the bolt heads and the end walls of the recesses 36. The contact members 29, 30, 31 and 32 are normally in engagement, respectively, with stationary contact terminals 37, 38, 39 and 40 which are rigidly secured to an insulating plate 41; said plate being supported upon a bracket 42 with which one of the side frames 10 of the core member 1 is provided.

35 The box 26 is provided with a frame comprising side strips 43 and a cross piece 44, the former being of such length that the latter may be above the rectifier bulb which projects above the top of the box. A vertical rod 45, having a handle 45^a at its upper end, is secured to the cross piece 44. The side strips 43 are provided with grooves 46 to receive stationary guide strips 47 that are supported by brackets 48 and 49 on the side frames 10 and extend from the stationary plate 41 to the top of the tank 8.

Directly above the rectifying device, the cover member 9 is provided with an opening 50 which is normally closed by a hinged cover 51, the size of the opening and the arrangement of parts being such that the rectifying device, together with the box 26, may be readily removed from the tank by means of the rod 45 and handle 45^a.

55 The rectifier bulb 20 may be rocked in order to facilitate its starting, in accordance with a well known practice, by means of a hand wheel 52 on the outer end of a shaft 53 that extends through the wall of the cover member 9 and is journaled in a bearing block 54, the inner end of the shaft being provided with a crank 55 that is connected to a projection 56 of the rocking frame 25 by means of a rod 57.

65 The starting transformer 7 comprises a

core member 58 that is supported upon the side frame 10 by means of a bracket 59, a primary winding 60 and a secondary winding 61. The core member 58 is composed of sheet metal punchings which are bolted between a plate 62^a and the bracket 59.

70 The arrangement of parts is such as to effect a maximum economy in the space occupied, and the efficiency of the device, as a whole, is materially improved by reason of 75 the fact that the rectifying device, the starting transformer and the regulator proper are all inclosed in a single casing which may preferably be filled with oil or other insulating fluid for conducting away the heat generated in the current-conducting parts and 80 in the magnetizable core members.

The operation of, and the circuit connections for, the device may be described and traced as follows, reference being had to Fig. 85 9 of the drawings: Alternating current energy may be supplied from any convenient source, through conductors 62 and 63, to the movable primary coils 4 and 5. The secondary coils 2 and 3 are connected in series 90 with each other and the terminals of the group are connected to the positive terminals 21 and 22 of the rectifying device. The middle point of the secondary group is connected to one terminal of an external uni-directional current circuit 64, the opposite end of which is connected to the middle point of the secondary winding 61 of the starting transformer 7. The extremities of 95 the secondary winding 61 are connected to 100 the negative terminals 23 and 24 of the rectifier bulb and the primary winding 60 is connected to a coil 66 which surrounds the intermediate leg of the core member 1 and serves as a source of energy for the starting 105 transformer.

In starting the rectifying device, the hand wheel 52 is rotated to tilt the rectifier bulb sufficiently to spill mercury from the one protuberance to the other and to form a 110 bridge of mercury between the terminals 23 and 24. When this condition obtains, the transformer winding 61 is short circuited through the mercury and a current flows in the one direction or the other which is sufficient to vaporize a portion of the mercury and to start the rectifying process. Under normal operation, the uni-directional currents flow from each of the terminals 23 and 24 through one half of the winding 61 115 in opposite directions, the return circuit being established as above indicated through conductor 64, which may constitute a series arc lamp circuit, to the middle point of secondary coils 2 and 3. The movable coil 120 regulator proper acts in a well known manner to maintain substantially constant current on the external circuit.

125 It will be understood that various structural modifications may be effected within 130

the spirit and scope of my invention and I desire that only such limitations shall be imposed as are indicated in the appended claims.

5 I claim as my invention:

1. In electrical apparatus, the combination with a regulator having relatively movable coils, and an inclosing casing therefor, of a current-rectifying device tiltingly 10 mounted within the casing and having a starting coil that is energized by current from one of the regulator coils.

2. In electrical apparatus, the combination with a regulator having relatively 15 movable coils and an inclosing casing therefor, of a current-rectifying device having a starting coil that is energized by current from one of the regulator coils, and a box or casing in which said device is tiltingly 20 and removably supported.

3. In electrical apparatus, the combination with a current-regulating device having a magnetizable core member, relatively movable coils associated therewith, and an 25 auxiliary coil influenced by the core member, of a mercury-vapor rectifying device electrically connected to the regulator, and a starting transformer energized from said auxiliary coil.

30 4. In electrical apparatus, the combination with a regulator having a magnetizable core member, stationary and movable coils and a low-voltage secondary coil, of a current-rectifying device having two negative 35 terminals, a starting transformer having two windings respectively connected across the terminals of the current rectifier and to the low-voltage secondary coil of the regulator.

40 5. In electrical apparatus, the combination with a stationary core member, sta-

tionary and movable coils influenced thereby and an auxiliary coil encircling the main path of the magnetic flux, of a mercury-vapor rectifying device having two primary 45 terminals connected to the main secondary circuit of the regulator and two negative terminals, and a starting transformer for the rectifier having two windings which are respectively connected across the negative 50 terminals of the rectifier and to the auxiliary coil of the regulator.

6. In electrical apparatus, the combination with a stationary core member, stationary secondary coils and movable primary coils therefor, and a stationary auxiliary coil influenced thereby, of a mercury-vapor rectifying device comprising a bulb having two positive terminals, two protuberances containing mercury and having 55 negative terminals connected thereto, a starting transformer having a primary winding connected to the auxiliary coil of the regulator, and a secondary winding connected across the negative terminals of the 60 rectifier, an alternating current supply circuit connected to the primary coils of the regulator and uni-directional current-receiving circuit connected from the middle point of the starting transformer secondary 65 winding to the point of connection between the secondary coils of the regulator, said coils being connected in series across the positive terminals of the rectifier. 70

In testimony whereof, I have hereunto 75 subscribed my name this 27th day of March, 1908.

FRANK CONRAD.
